DRIVE AND CONTROL FOR AUTOMATIC MUSICAL INSTRUMENTS

Peter T. Calamari, Deep River, and Paul F. Murdock, Clinton, Conn., assignors to The Aeolian Company, New York, N. Y., a corporation of Connecticut

Application July 21, 1949, Serial No. 106,056

24 Claims. (Cl. 84—126)

1

This invention relates to automatic musical instruments and to automatic player mechanisms for musical instruments wherein the music is reproduced automatically under the control of a perforated note sheet.

It is an object of the invention to provide improved automatic musical instruments and player mechanisms of the class described. It is an object of the invention to provide improved transmission and clutch mechanisms for rotating the takeup spool during the playing operation and for rerolling the perforated note sheet on to the music roll spool upon conclusion of the playing operation. It also is an object of the invention to provide improved pneumatic controls for governing the operation of the transmission and clutch mechanisms. It is a further object to provide an improved tempo control. Other objects and advantages of the invention will appear hereinafter.

A preferred embodiment of the invention has been selected for purposes of illustration and description and is shown in the accompanying drawings wherein:

Figure 1 is a front elevation of the transmission and clutch mechanisms for rotating the takeup spool and for rotating the music roll spool to reroll the perforated note sheet thereon, some of the parts being removed and others broken away in section to disclose the construction more clearly;

Figure 2 is an end elevation of the transmission and clutch mechanisms looking toward the right hand side of Figure 1, some of the parts being removed and others broken away in section to disclose the construction more clearly;

Figure 3 is a schematic diagram showing the pneumatic controls which govern the operation of the transmission and clutch mechanisms; and

Figures 4 and 5 are views corresponding, respectively, to Figures 1 and 2, but showing modifications in certain features of the construction.

In automatic musical instruments employing a perforated note sheet for governing the operation of the note striking means it is customary to use a takeup roll for drawing the perforated note sheet from the music roll spool, the note sheet moving over a tracker bar as it passes to the takeup roll. As the note sheet moves across the tracker bar, the perforations in the note sheet permit air to enter the tracker bar ports and flow through the connecting tubes to the corresponding action pneumatics, which operate the key striking means.

Upon conclusion of the playing operation, the

2

driving connection to the takeup spool is interrupted and the music roll spool is rotated to reroll the note sheet thereon preparatory to removing the music roll from the instrument, or to replaying the selection if desired. During the rerolling operation the note sheet again moves across the tracker bar, but the player mechanism should be rendered inactive at this time by suitable controls, so that no notes will be struck.

10 Referring first to Figure 1 of the drawings, 11 represents a side wall of the spool box of the automatic instrument. Within the spool box there is a pair of aligned spindles for removably holding a music roll, one end of the music roll 13 and the driving spindle 15 being shown. Also within the spool box is a second pair of aligned spindles, below and parallel to the first pair, for holding a takeup spool, one end of the takeup spool 14 and its driving spindle 16 being shown. The connections between the music roll spool 13 and spindle 15, and between takeup spool 14 and spindle 16 are keyed or otherwise constructed so that the spools will be driven by their respective spindles.

15 25 The perforated note sheet passes over the tracker bar, indicated at 12, as it moves from one spool to the other spool during the playing and rerolling operations.

The spindles 15 and 16 are mounted in suitable bearings 17 and 18 in the wall 11 of the spool box and extend some distance out beyond the wall as may be seen in Figure 1. The outer end of the spindle 15 is provided with an axial bore 19 and a port 21 through the spindle wall adjacent the inner end of the bore. The outer end of the spindle 16 is similarly provided with an axial bore 20 and port 22. These openings in the ends of the spindles are employed in operating the clutch mechanisms which connect the spindles, selectively, to the power transmission to cause one or the other spindle to rotate and turn the spool associated therewith, as will appear more fully hereinafter.

20 25 Free to turn on the spindle 15 is a worm wheel 23 to which a clutch plate 25 is rigidly secured so as to turn therewith on the spindle. A cooperating clutch plate 27 is keyed or otherwise secured to the spindle 15 so as to turn therewith. A slight movement of the plate 25 is permitted 30 along the spindle 15 toward and away from the clutch plate 27 for the purpose of engaging and disengaging the two clutch plates. These plates are shown disengaged.

25 One of the clutch plates, 27 in the illustrative embodiment, has a narrow marginal facing of

rubber or the like on its inner surface to insure a tight and good driving connection between the plates when the clutch is engaged.

It will be noted that the port 21 through the spindle wall is located between the clutch plates 25 and 27. By applying suction to the bore 19, air will be withdrawn from between the clutch plates, thus reducing the air pressure therebetween, and the atmospheric pressure acting against the outer face of the clutch plate 25 will cause that plate to move along the spindle 15 toward the clutch plate 27 and engage the clutch. If the gear 23 is being driven, the spindle 15 then will rotate. Upon discontinuance of the suction the clutch plates will no longer be held together and the driving connection to the spindle 15 will be broken.

On the outer end of the spindle 15 is a control block 29. The spindle is free to turn within the control block and, as may be seen in Figure 2, the latter is provided with a tubular connection 31 for applying suction to the axial bore 19.

Movably mounted in the control block 29, parallel to the spindle 15, is a tubular brake shoe 33 having a facing 35 of leather or the like adjacent the outer face of the clutch plate 27. Application of suction to the outer end of the tubular brake shoe 33 will serve to draw the brake shoe and clutch plate 27 together. This will cause a slight drag on the reroll clutch plate 27 and keep the music roll paper snug against the tracker bar while the instrument is playing. As will appear hereinafter, suction is applied to the brake shoe 33 only during the playing operation.

Free to turn on the spindle 16 is a combined worm wheel and clutch plate 26, the gear teeth being formed around the periphery of the clutch plate. A cooperating clutch plate 28 is secured on the spindle 16 so as to turn therewith, much as clutch plate 27 is secured on its spindle 15. One of the clutch plates, 28 in the drawings, has a narrow marginal facing of rubber or the like to insure a tight connection between the plates when the clutch is engaged. The port 22 of the spindle 16 is located between the clutch plates 26 and 28, so that the application of suction to the axial bore 28 will cause the plate 26 to move along the spindle until it engages the plate 28, thus completing a driving connection between the worm wheel 26 and the spindle 16. Clutch plates 26 and 28 are shown engaged.

The perforated note sheet may be rerolled at much higher speed than is permissible for playing. This accounts for the difference in size of the worm wheels 23 and 26 on the two spindles. It is immaterial to the invention whether a worm wheel and its associated clutch plate are made in one piece, as in the case of the combined worm wheel and clutch plate 26, or are made separately and connected so as to turn together, as worm wheel 23 and clutch plate 25.

Mounted on the outer end of the spindle 16 is a control block 30 similar to the control block 29. Carried by the control block 30 is a tubular brake shoe 34 having a facing 36 of leather or the like for exerting a drag on the clutch plate 28 when suction is applied to the outer end of this brake shoe.

As may be seen in Figure 2, a tubular connection 38 is made between the suction connection 32 in the control block 30 and the tubular brake shoe 34 mounted in the control block 29. When suction is applied through the tubular connection 32, as during the playing operation, it causes the clutch plates 26 and 28 to engage each other and,

if the combined worm wheel and clutch plate 26 is turning, the takeup spool 14 will be rotated to draw the note sheet from the music roll 13 over the tracker bar 12. At the same time, suction will be applied through the tube 38 to the brake shoe 34 to cause it to exert a drag on the clutch plate 28, thus applying sufficient tension on the note sheet to hold it firmly against the tracker bar.

A similar tubular connection 37 is made between the suction connection 31 in the control block 29 and the tubular brake shoe 34 mounted in the control block 30. When suction is applied to the tubular connection 31, as during the re-rolling operation, it causes the clutch plates 25 and 27 to engage each other and, if the gear 23 is turning, the music roll spool 13 will be rotated to reroll the note sheet from the takeup spool 14 onto the music roll spool. At the same time, suction will be applied through the tube 37 to the brake shoe 34 to cause it to exert a drag on the clutch plate 28 and thus prevent over-running of the takeup spool at the relatively high re-rolling speed.

From the foregoing it will be evident that the clutch mechanisms of the present invention may be selectively engaged, either to cause the takeup spool to withdraw the perforated note sheet from the music roll over the tracker bar under controlled tension, or reroll the music roll under controlled tension at high speed, merely by applying suction to one or the other of the tubular connections 31 and 32.

The power transmitting means for driving the worm wheels 23 and 26 will now be described. Engaging the worm wheel 23 is a left hand worm 39, and engaging the worm wheel 26 is a right hand worm 40. The worms 39 and 40 are secured on opposite ends of the shaft 41 in such manner as to turn therewith. The shaft 41 is rotatably secured by brackets 42 to the side wall 11 of the spool box, in such a position that the worms 39 and 40 are in operative engagement, respectively, with the worm wheels 23 and 26.

Slidably mounted on the shaft 41, between the brackets 42, is a sleeve 43, to one end of which is rigidly secured a wheel 44. This wheel has a rounded edge of frictional material for engagement with a driving wheel 47. The sleeve 43, which serves as a guide for the friction wheel 44, is slotted throughout most of its length, as shown at 45, to receive the end of a guide pin 46 firmly secured in the shaft 41. This connection causes the sleeve 43 and friction wheel 44 to turn with the shaft 41, while permitting limited, relative longitudinal movement.

Engaging the friction wheel 44 is the drive wheel 47, which is a disk mounted on the end of the drive wheel spindle 48. The flat face of the drive wheel which engages the friction wheel 44 is made of suitable frictional material so that rotation of the drive wheel 47 will cause the friction wheel 44 to turn except, of course, when the friction wheel is directly on the center of the drive wheel.

By shifting the friction wheel guide 43 along the shaft 41 it will be possible to vary the speed of rotation of the shaft by any desired amount from zero up to the maximum speed when the tread of the friction wheel reaches the edge of the drive wheel.

This arrangement permits precise tempo control while the musical instrument is playing. The position of the friction wheel 44 on the drive wheel 47 conveniently may be varied by sliding

the friction wheel bracket 49 along the shaft 41, the bracket 49 shifting the guide sleeve 43 and friction wheel 44 along the shaft with it as it moves. The adjustment may be regulated in any suitable manner, for example by means of a pivoted tempo control lever 50, one end of which is connected in suitable manner to the friction wheel bracket 49 and the other end of which is connected, as by means of a wire 51 or the like, to a tempo indicator and control, not shown.

The drive wheel spindle 48 is supported in a suitable bearing 52, within a sleeve 53, secured to the drive wheel support bracket 54. The outer end of the drive wheel spindle is connected, desirably by means of a flexible and sliding coupling 60, to one end of the drive shaft 55. The drive shaft 55 may be connected at its other end directly or through suitable speed reduction mechanism to a small electric motor, not shown.

Desirably the drive wheel spindle bearing 52 has a slight freedom of movement longitudinally in the sleeve 53, so that the drive wheel 47, which engages the friction wheel 44 for turning the shaft 41, may be moved off of the friction wheel. This will permit easy adjustment of the tempo control when the electric motor is not running. Otherwise, the friction between the drive wheel and the friction wheel might make such adjustment a little more difficult.

Desirably the button 56 which controls the motor switch is connected through the cam lever 57 and the cam 58 on the sleeve 53 so that when the switch is in "off" position the drive wheel 47 will be moved slightly out of engagement with the friction wheel 44, and when the switch is in "on" or "play" position the drive wheel 47 will be pressed lightly against the friction wheel 44.

The tension of the spring 59, connected between the cam lever 57 and the drive wheel support bracket 54, determines the pressure exerted by the drive wheel 47 against the friction wheel 44.

It will be evident from the foregoing description that a very fine adjustment of the tempo is possible and that notwithstanding the nature of the variable speed mechanism which permits such fine adjustment, it is possible to regulate the tempo control to any desired setting while the motor is not running, as well as when the motor is running.

Next will be described the pneumatic control means whereby the player may be set at the will of the operator either to play a selection, reroll the note sheet and shut off the instrument, or to play a selection, reroll the note sheet and replay the selection repeatedly, all without further action on the part of the operator. Moreover, the control means, once it has been set by the operator for either condition, depends for its further operation on the covering and uncovering by the perforated note sheet of a single port in the tracker bar.

Figure 3 of the drawings is a schematic diagram of the control mechanism to be described. For purposes of clarity the suction tubes are shown, for the most part, as single lines on the drawing. Where these lines merely cross each other on the drawing there is no interconnection between the tubes. Corresponding parts in Figures 1 and 2 are designated by the same reference numbers as in Figure 3, and as the description proceeds it will be desirable to refer to all figures for a full understanding of the operation.

The reference number 92 represents the front wall of the player housing, against which the control buttons 56, 93 and 95 are mounted. Let

us suppose that all of the control buttons are pushed in against the wall 92, or in inactive position, and that it is desired to play a selection once and then to shut off the instrument after the note sheet has been rerolled.

When the electric switch 61 is turned on by pulling out the "start and stop" button 56 as shown in Figure 3, the electric motor connected to the drive shaft 55 (Figure 1) will be started and the motor which drives the vacuum pump supplying suction for operating the musical instrument and its controls also will be started. The vacuum pump, which is not shown, supplies suction through the tube 62 to the junction block 63.

Suction is supplied from the junction block 63 to the tube 64 connected to the stationary member of the clutch control valve 65. This suction is fed through the movable member of the clutch control valve 65 and the tube 66 to the tubular connection 32 of the control block 30. This causes air to be exhausted from between the "play" clutch plates 26 and 28, and the surrounding atmospheric pressure causes the plates to be pressed firmly together. With this clutch closed, the takeup spool 14 is driven to draw the perforated note sheet from the music roll 13, over the tracker bar 12, and onto the takeup spool.

While the player mechanism is operating, suction from the tube 32 also is admitted through the control block 30 and the tube 38 to the "play" brake 33. This suction between the play brake 33 and the reroll clutch plate 27 causes a slight drag on the music roll paper, insuring that the paper will be pressed firmly against the tracker bar during the playing operation.

When the end of the music roll is reached, the reroll control port 3T, for example the third hole from the treble end of the tracker bar, normally closed by the moving note sheet, is opened by a corresponding perforation in the note sheet. Atmosphere is thus admitted through the port 3T to the tube 67 connected to the stationary member of the reroll valve block 68, and passes therefrom through tube 69 to the chamber on the rear side of the reroll control diaphragm 70. This chamber also is connected through a restricted passageway or bleeder 83 and tube 89 to suction in the junction block 63. The chamber enclosing the front side of the diaphragm 70 is similarly connected through a bleeder 90 and tube 91 to suction in the junction block 63. The atmosphere admitted through the tube 69 to the rear chamber pushes the diaphragm 70 forward, and through its mechanical connection 71 moves the clutch control valve 65 to the "reroll" position. The mechanically connected reroll button 93 is thus moved out away from the wall 92.

With the clutch control valve 65 in this condition, atmosphere is admitted through a port in the valve to the tube 66 and connection 32, which releases the "play" clutch plates 26 and 28. Suction from the tube 64 is now connected through the clutch control valve 65 and the tube 72 to the tubular connection 34 in the control block 29. This causes air to be exhausted from between the "replay" clutch plates 25 and 27 and the surrounding atmospheric pressure presses these clutch plates firmly together to engage this clutch. Now the rotation of the transmission drive shaft rotates the spindle 15 in the reverse direction and the perforated note sheet is rerolled onto the spool 13.

While the music roll is rerolling, suction also is admitted from the connection 31 through the control block 29 and the tube 37 to the reroll brake 34. The suction exerted on the play clutch plate 28 by the reroll brake 34 causes a slight drag on the takeup spool and prevents the note sheet from unwinding faster than it can be taken up by the music roll spool.

With the clutch control valve 65 in the reroll position, atmosphere is admitted through the port 73 in the movable member of the control valve to the tube 74. This atmosphere passes through the tube 74, T nipple 87 and tube 75 to the under side of the action cut-out diaphragm in the action cut-out block, not shown. The atmosphere thus admitted to the cut-out block causes the cut-out diaphragm to raise and cut off all suction to the player action while the music roll is rerolling, thus preventing the striking of any notes during the rerolling operation.

As the music roll starts to reroll, pin 76 in the spindle 16 causes the movable member of the reroll valve block 68 to be turned to the left, as viewed in Figure 3, to the reroll position. In this position, the tubes 67 and 69 are disconnected and the tubes 67 and 77 are connected through the reroll valve block 68.

The pin 76 may be mounted in the hub of the clutch plate 28. As the spindle 16 rotates, the end of the pin engages the free end of the thin flat spring 96, which is secured at its other end to the pivotally mounted member of the reroll valve block 68. Pressure of the pin against the flat spring causes the movable member of the reroll valve block to be turned within its limited range of movement, and the spring then flexes to let the end of the pin slip off the end of the spring. Upon rotation of the spindle 16 in the opposite direction, the pin 76 will engage the spring 96 to turn the movable member back to the position shown in Figure 3.

When the music roll has rewound so that the tapered end of the roll again uncovers the 3T hole in the tracker bar, atmosphere is admitted therethrough to the tube 67, reroll valve block 68, tube 77, and thence through the T nipple 78 and tube 79 to the replay valve block 80.

This atmosphere then passes through the replay valve block 80 at the "off" position and through the tube 81 to the chamber enclosing the front side of the electric switch control diaphragm 82. The chamber enclosing the rear side of the diaphragm 82 is connected through tube 94 to suction in the junction block 63. The atmosphere admitted through tube 81 to the front chamber pushes the diaphragm 82 to the rear and through its mechanical connection 83 shuts off the electric switch 61 and moves the start and stop button 56 inwardly to its original stop position.

At the same time, atmosphere from the tracker port 3T is admitted through the T nipple 78 and tube 84 to the chamber enclosing the forward side of the reroll control diaphragm 70. Under the pressure of the atmosphere the diaphragm 70 is moved to the rear and through its mechanical connection 71 to the clutch control valve block 65 the diaphragm resets this block in the play position.

While the reroll valve block 68 is in the reroll position, port 85 in the movable member of the block admits atmosphere to the tube 86 and through a T nipple connection 87 to the tube 75 and thence to the under side of the action cut-out diaphragm (not shown) to cut off suction

to the player action and prevent notes being played during the time the tapered end of the music roll allows holes to be uncovered in the tracker bar at the end of the reroll operation.

If it is desired to replay a music roll instead of shutting off the instrument after the roll has been played and rerolled, the replay valve block 80 is set to the "on" position by pulling out the replay button 95. Then when the start and stop button 56 is pulled out, the controls will function to cause the music roll to be played and to be rerolled as described above, but instead of the instrument being shut off following the rerolling operation, the selection will be replayed, and this cycle will be repeated automatically until the operator changes the setting of the control buttons.

The setting of the replay valve block 80 to the "on" position disconnects the tubes 79 and 81 in the replay valve block 80, so that when the music roll has been rewound and the 3T hole in the tracker bar is uncovered, atmosphere is not admitted to the chamber enclosing the forward side of the electric switch diaphragm 82. Hence, the electric switch 61 is not turned off and the start and stop button 56 remains in its outer or play position.

Atmosphere from hole 3T does pass to the chamber enclosing the forward side of the reroll control diaphragm 70 and causes this diaphragm to move the clutch control valve block 65 from the reroll position to the play position. This causes the music roll to be replayed, and upon completion of this replaying the roll will again be replayed, and this cycle of operations will repeat itself automatically until the setting of the controls is changed by the operator.

Summarizing, when the "start and stop" button 56 only is pulled out, with a music roll in the machine, the selection will be played, the perforated note sheet will be rerolled, the reroll controls will be reset ready to play, and the start and stop button will be returned to its "off" position, all automatically under the control of a single port in the tracker bar. If both the "start and stop" button 56 and the "replay" button 95 are pulled out the selection will be played, the perforated note sheet will be rerolled, the reroll controls will be reset for playing, and the selection will be replayed, and this cycle of operations will be repeated automatically and continuously under the control of the same port in the tracker bar until one of the buttons 56 and 95 is pushed in to its "off" position.

The structure shown in Figures 4 and 5 of the drawings is similar to the embodiment disclosed in Figures 1 and 2, except for modified braking means for the roll spindle clutches, and an alternate means for engaging and disengaging the friction disk and friction roller. Certain parts of the structure not necessary to the disclosure of these modifications have been omitted for simplicity. Corresponding parts are identified by the same reference numbers, and the following description of the construction and operation of Figures 4 and 5 will be limited to the differences in structure.

In the modified structure of Figures 4 and 5, the control blocks 29 and 30 are not provided with tubular brake shoes 35 and 36, and, of course, there are no tubes 37 and 38. Clutch plates 25 and 27 may be engaged by applying suction through the tube 31 to the control block 29, and clutch plates 26 and 28 may be engaged by applying suction through the tube 32 to the con-

trol block 30, all in the manner hereinabove described with reference to Figures 1 to 3.

Mounted on the upper part of the drive wheel support bracket 54, as by means of a screw 97, are a small plate 98 and the spring 99. Secured to the spring 99 near its other end is a brake shoe 100, for example, a block of wood with suitable facing material where it bears against the clutch plate 27 under the pressure of the spring 99.

Desirably the brake shoe 100 is secured near one edge to the spring 99, by a hinge connection. For example, a staple 101 may be driven through holes in the spring 99 into the brake shoe 100, and if the staple is not driven home this will provide a hinge connection satisfactory for the purpose to be hereinafter described.

During the playing operation the clutch plate 27 turns to the left, as viewed in Figure 5, and the entire braking surface of the brake shoe 100 bears against the face of the clutch plate under the pressure of the spring 99. Thus, rotation of the spindle 15 is retarded sufficiently to insure that the perforated note sheet always will be maintained against the tracker bar under tension during the playing operation.

When the clutch plate 27 turns in the opposite direction, as during the rerolling operation, the brake shoe 100 turns partly about its pivoted connection and only the leading corner or edge of the braking surface will bear against the face of the clutch plate 27. The braking effect will be greatly reduced as compared to when the clutch plate rotates in the opposite direction, thus facilitating high speed rerolling of the music sheet.

The pressure of the spring 99 against the brake shoe 100 may be made adjustable to regulate the braking action. This may be done, for example, by the screw 102 extending through an opening in the spring and engaging a screw threaded opening in the plate 98. As shown, the spring 99 is bent slightly, so that normally it does not lie flat against the plate 98.

A brake similar to that just described for the clutch plate 27 also may be provided for the clutch plate 28, if desired. However, satisfactory operation has been obtained when the brake for the clutch plate 28 applies the same braking pressure both during the playing and the rerolling operations.

As shown in Figures 4 and 5, there is mounted on the lower part of the drive wheel support bracket 54, as by means of screw 103, a small plate 104 and spring 105, the latter having secured to its outer end a brake shoe 106 bearing against the clutch plate 28. The construction is similar to that described for the clutch plate 27, except that there is no hinge connection between brake shoe 106 and the spring 105. The pressure exerted by the spring 105 on the brake shoe 106 may be adjusted by means of screw 107, in the manner described hereinabove for the spring 99 and the screw 102.

The alternate means for engaging and disengaging the friction disk or drive wheel 47 and the friction wheel or roller 44 is shown in Figure 4 of the drawings. The bearing 52 for the drive wheel spindle 48 is engaged by a fork 111 secured on the movable board of a pneumatic actuator 112. The stationary board of the pneumatic 112 is secured to the sleeve 53 by means of a support bracket 113. A coil spring 114 is secured at one end to the fork 111, and at its other end to a fixed part of the player structure, for ex-

ample, the mounting for the electric driving motor.

Normally the spring 114 pulls the fork 111 to the right, as shown in Figure 4, and moves the bearing 52 and drive wheel spindle 48 with it to disengage the drive wheel or disk 47 from the friction wheel 44, thus breaking the driving connection.

When the start and stop switch for the player 10 is turned on, suction is applied to the pneumatic 112 through tube 115, which is connected to the junction block 63 (Figure 3). The suction collapses the pneumatic 112, overcoming the tension exerted by the spring 114, and the fork 111 15 moves the bearing 52 and drive wheel spindle 48 to the left, to press the drive wheel 47 against the friction wheel 44.

When the start and stop switch is opened, the suction stops, and the spring 114 opens the pneumatic 20, pulling the drive wheel 47 away from the friction wheel 44. The tension on the spring 114 conveniently may counteract about one half of the pull exerted by the pneumatic when suction is applied thereto. By changing the spring 25 tension it is possible to regulate the pressure between the friction disk 47 and roller 44.

It will be apparent from the foregoing description that we have provided improved clutch and transmission mechanisms for automatic 30 musical instruments and players. Moreover, we have provided simplified and improved pneumatic controls for governing the operation of automatic musical instruments.

The invention herein disclosed may be variously 35 modified and embodied within the scope of the subjoined claims.

We claim as our invention:

1. In an automatic musical instrument of the type in which a perforated note sheet is moved 40 from a music roll across a tracker bar to a take-up spool, in combination, a tracker bar, a take-up spool for moving a perforated note sheet from a music roll across the tracker bar, a spindle for driving the take-up spool, a spindle for driving 45 the music roll to reroll the note sheet, a clutch for each spindle, each clutch comprising a driven member free to rotate on the spindle and a co-operating member keyed to the spindle, and pneumatic means for selectively engaging the 50 clutches to drive the take-up spool, or to reroll the note sheet.

2. An automatic musical instrument according to claim 1, characterized by the fact that the driven and the cooperating clutch members on 55 each shaft are movable relative to each other along the shaft by changing the air pressure between the clutch members to engage and disengage the clutch, and further characterized by means for changing the air pressure between 60 the clutch members.

3. An automatic musical instrument according to claim 2, characterized by the fact that the clutch members on each spindle are closely spaced plates, and that one of the opposing plate 65 faces has a continuous raised marginal portion which bears against the face of the other plate when the clutch is engaged.

4. In an automatic musical instrument of the type in which a perforated note sheet is moved 70 from a music roll across a tracker bar to a take-up spool, in combination, a tracker bar, a take-up spool for moving a perforated note sheet from a music roll across the tracker bar, a spindle for driving the take-up spool, a spindle for driving 75 the music roll to reroll the note sheet, a clutch

for each spindle, each clutch comprising a driven member free to rotate on the spindle and a co-operating member keyed to the spindle, an axial bore extending from one end of each spindle to a point adjacent the clutch members on the spindle, a port through the wall of each spindle adjacent the clutch members, means actuated by varying the pneumatic pressure in the bore of a spindle to engage the clutch thereon, and means for changing the air pressure within the bores of the spindles to selectively engage the clutches to drive the take-up spool, or to reroll the note sheet.

5. An automatic musical instrument according to claim 4, including a controlled source of exhaust connected to each bore through the end of the spindle for actuating the clutch.

6. An automatic musical instrument according to claim 4, in which the driven and the co-operating clutch members on each spindle are closely spaced plates movable relative to each other along the spindle, and in which a valve-controlled source of exhaust is connected through an axial bore in one end of the spindle and a port in the spindle wall to the space between the clutch plates for reducing the pressure between the plates, thus causing the plates to be forced together by the surrounding atmosphere to engage the clutch.

7. In an automatic musical instrument of the type in which a perforated note sheet is moved from a music roll across a tracker bar to a take-up spool, in combination, a tracker bar, a take-up spool for moving a perforated note sheet from a music roll across the tracker bar, a spindle for driving the take-up spool, a driving shaft, a clutch connecting the spindle to the driving shaft, said clutch comprising one member rotatably mounted on the take-up spool spindle and driven by the driving shaft, and a cooperating member keyed to turn with the take-up spool spindle, and pneumatic means for engaging the cooperating clutch members to turn the take-up spool spindle.

8. In an automatic musical instrument according to claim 1, in combination, a brake for each of the clutch members which is keyed to a spindle, and means for selectively applying the brakes to the said clutch members to create a drag on the rotation thereof and of the associated spindle.

9. In an automatic musical instrument according to claim 1, in combination, a brake for each of the clutch members which is keyed to a spindle, and control means for automatically applying the brake to the clutch member on one spindle when the clutch on the other spindle is engaged.

10. In an automatic musical instrument according to claim 1, in combination, a brake for each of the clutch members which is keyed to a spindle, and means for applying the brake to the music roll spindle clutch member during the playing operation and for releasing the brake pressure on the music roll spindle clutch member during the rerolling operation, all automatically in response to the direction of rotation of the spindle.

11. In an automatic musical instrument according to claim 1, in combination, a brake shoe held under resilient pressure against the clutch member keyed to one of the spindles, the holding means for the brake shoe causing a large area of the brake shoe to be pressed against the clutch member when the clutch member turns in one

direction, and a relatively small area of the brake shoe to be pressed against the clutch member when the clutch member turns in the opposite direction, all automatically in response to the direction of rotation of the spindle.

5. In an automatic musical instrument according to claim 1, in combination, a brake for one of the clutch members, said brake comprising a brake shoe, means for resiliently pressing an extended surface of the brake shoe against the clutch member when the latter turns in one direction, and a hinge connection between the brake shoe and the said means, whereby the brake shoe turns partially about the hinge connection when the clutch member turns in the opposite direction, to disengage most of the brake shoe surface from the clutch member.

10. In an automatic musical instrument of the type in which a perforated note sheet is moved from a music roll across a tracker bar to a take-up spool, in combination, a tracker bar, a take-up spool for moving a perforated note sheet from a music roll across the tracker bar, clutch-controlled means for driving the take-up spool, 15 clutch-controlled means for driving the music roll to reroll the note sheet, a brake for the music roll, a brake for the take-up spool, pneumatic means for selectively engaging the clutches either to drive the take-up spool or to reroll the note sheet, and means for automatically applying the brake to the music roll when the take-up spool is being driven, and for automatically applying the brake to the take-up spool when the note sheet is being rerolled.

20. In an automatic player mechanism for a musical instrument of the type in which a perforated note sheet is moved from a music roll across a tracker bar to a take-up spool, in combination, a tracker bar, means for driving the take-up spool, means for driving the music roll 25 to reroll the note sheet, a replay control, means controlled by a port in the tracker bar which is exposed to the atmosphere by a perforation in the note sheet at the end of the playing operation to actuate the driving means for the music roll to cause the note sheet to be rerolled, and means controlled by exposure of the same port at the end of the rerolling operation to shut off the reroll mechanism and either actuate the 30 means for driving the take-up spool and cause the note sheet to be replayed, or shut off the player mechanism, depending upon the setting of the replay control.

35. In an automatic player mechanism for a musical instrument in which a perforated note sheet is moved from a music roll across a tracker bar to a take-up spool, in combination, a reroll valve block, means for automatically setting the reroll valve block in one position during the playing operation and in another position during the rerolling operation, means controlled by the admission of air through a port in the tracker bar and through the reroll valve block when in the first position to set the reroll mechanism into 40 operation, and means controlled by the admission of air through the same tracker bar port and through the reroll valve block when in the second position to turn off the reroll mechanism.

45. In an automatic player mechanism for a musical instrument according to claim 15, in combination, means actuated by rotation of the driving spindle for the take-up spool during the playing operation to set the reroll valve block into position so that it will start the reroll mechanism when the said tracker bar port is uncov-

ered by the perforated note sheet, and actuated by rotation of the driving spindle during the re-rolling operation to set the reroll valve block into position to turn off the reroll mechanism when the said tracker bar port is again uncovered by the perforated note sheet.

17. An automatic player mechanism for a musical instrument according to claim 16, in which the said means for changing the setting of the reroll valve block comprises a pin extending transversely through the driving spindle and a flat spring secured to the movable member of the reroll valve block, the pin and the spring being so located relative to each other than the pin engages the spring during every turn of the spindle.

18. In an automatic player mechanism for a musical instrument according to claim 15, and in which the music roll and take-up spool are supported by pairs of aligned spindles, in combination, a pin fixed transversely in one of the spindles, a light flat spring secured by one end to the movable member of the reroll valve block, the parts being so arranged relative to each other that upon rotation of the spindle an end of the pin fixed therein will engage the spring and slide off the free end thereof, moving the reroll valve block to one of its aforesaid positions, depending on the direction of rotation of the spindle, provided the valve block has not already been moved to this position by the pin and spring.

19. In an automatic player mechanism for a musical instrument of the type in which a perforated note sheet is moved from a music roll across a tracker bar to a take-up roll, in combination, a tracker bar, a take-up spool for moving a perforated note sheet from a music roll across the tracker bar, driving means, power transmitting means for connecting the driving means to the take-up spool during the playing operation, and to the music roll to reroll the note sheet, said power transmitting means including a disk and roller friction drive, and a tempo control for varying the speed of the take-up roll during the playing operation, said tempo control comprising means for varying the position of the roller radially on the disk.

20. An automatic player mechanism according to claim 19, characterized by the fact that the

disk and roller friction drive includes a friction-faced disk secured on one end of a driving shaft and resiliently pressed against a friction-rimmed roller wheel mounted on a driven shaft, and means for adjusting the friction-rimmed roller wheel by minute increments along a radius of the disk from its center to its edge to vary the speed of rotation of the rolls.

21. An automatic player mechanism according to claim 19, including, in combination, means for automatically separating the friction disk and roller slightly when the player mechanism is turned off, so as to facilitate setting the tempo control prior to starting the player.

22. An automatic player mechanism according to claim 19, including, in combination, pneumatic means for resiliently pressing the disk against the roller of the friction drive.

23. An automatic player mechanism according to claim 19, including, in combination, pneumatic means for resiliently pressing the disk against the roller of the friction drive when the player mechanism is operating, and a spring for separating the disk and roller when the player mechanism is not in operation.

24. An automatic player mechanism according to claim 19, including, in combination, means continuously tending to separate the disk and roller, and means effective when the player mechanism is operating to overcome the first means and to cause the disk and roller to be resiliently engaged with each other in driving relation.
